PRINTING MECHANISM

Joseph F. Jirousek, Cleveland, Ohio, assignor to
The Chandler & Price Company, Cleveland,
Ohio, a corporation of Ohio

Application November 21, 1941, Serial No. 419,875

2 Claims. (Cl. 101—77)

This invention relates as indicated to printing mechanism, and more particularly to an improvement in lithograph presses of the type disclosed in my issued Patent No. 2,109,486.

When printing sheets on a cylinder press such as the aforementioned lithograph press disclosed in Patent No. 2,109,486, it is not infrequently desired to print some small local area of the sheet in a different color or to number the sheets consecutively, or the like. Sometimes, as when printing a sheet of checks, it is even desired to print a plurality of consecutive numbers on each sheet, such numbers also being consecutive from sheet to sheet. Prior to the invention of the press of the type disclosed in Patent No. 2,109,486, it was not possible to adapt the usual type of automatic numbering device, for example, to a lithograph printing press since the cylinders were disposed in a manner affording too little space for such attachment. Also, of course, in a lithograph press the impression cylinder has a metal surface affording an unsuitable platen for use in conjunction with the metal type of the usual numbering machine or other similar device.

It is, therefore, a primary object of this invention to provide an auxiliary printing mechanism adapted for use in conjunction with the usual metal impression cylinders of lithograph printing presses to print relatively small local areas of the sheets passing through such presses.

Another object of this invention is to provide a special numbering device and means for mounting the same which will be operative to number sheets as such sheets are carried around by the impression cylinder.

Other objects of this invention will appear as the description proceeds.

To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:

Fig. 1 is a front elevational view of the upper portion of a press showing the impression cylinder thereof and the manner of mounting the mechanism of my invention thereon;

Fig. 2 is a side elevational view of such portion of the press showing the driving and mounting means of my mechanism;

Fig. 3 is a cross-sectional view taken along the line 3—3 on Fig. 1;

Fig. 4 is a sectional view taken along the line 4—4 on Fig. 3 and showing the manner of mounting a numbering machine on its supporting cross shaft;

Fig. 5 is an end view of a printing roller of such numbering machine;

Fig. 6 is a view of the type face of such roller;

Fig. 7 is a sectional view through such roller taken along the line 7—7 on Fig. 5; and

Fig. 8 is a perspective view of a printing form optionally employable in accordance with one embodiment of my invention.

Now referring more particularly to such drawings, a pair of side members 1 and 2 are pivotally supported by brackets 3 and 4 carried by side frame members 5 and 6 respectively of the press. A cross shaft 7 is journaled between such side members 1 and 2 and is adapted to be rotated in timed relation with metal surfaced impression cylinder 8 by means of gears 9 and 10 respectively mounted on such shaft and cylinder. The rubber surfaced lithograph cylinder (not shown) is also driven in timed relation with such impression cylinder by means of gear 11 adapted to engage gear 10. Such lithograph cylinder with its gear 11 is journaled in sliding members such as 12 adapted to be moved in and out by adjustment of turn buckles such as 13 to move such lithograph cylinder in and out of operative engagement with impression cylinder 8, as disclosed in my aforesaid patent. The sheets being printed are fed between such lithograph and impression cylinders and carried around the impression cylinder to delivery conveyor means driven through bevel gears 14.

A short cylinder or wheel 15 is mounted on shaft 7 adapted to contact the end portion of cylinder 8 farthest removed from gear 10 to aid in maintaining the parallel alignment of shaft 7 thereto. One or more wheels 16 of smaller diameter than wheel 15 are keyed to shaft 7 by means of keys 17 for slidable movement therealong and adapted to be fixedly positioned thereon by means of set screws 18. Blocks 19 are adapted to be mounted as desired on the peripheries of such wheels 16 and held in place by means of screws 26. Such blocks are provided with keyways 21 in which printing devices, such as automatic numbering machines 22, may be secured by means of removable stops 23. Such numbering machines are provided with arms 24 carrying rollers 25 which may be operated to trip 55 and set such machines for the purpose of pro-

gressively bringing consecutive numbers into printing position. Such numbering machines are of the usual type made up of discs such as 26 adapted to be rotated by means of ratchet teeth 27 but bearing a rubber type face 28 instead of the usual metal type face since it is intended that such numbering machine cooperate with the metal surfaced impression cylinder 8 in imprinting the sheets as they are carried about the latter. Fingers 29 are provided mounted on shaft 30 and adapted to be adjustably positioned therealong by means of set screw 31, it being noted that said shaft 30 serves to pivotally connect the supplemental frame, comprising interconnected side members 1 and 2, with the main frame of the press. Such fingers are positioned to engage rollers 25 of the respective numbering machines as shaft 7 rotates and thus to set the numbering machines each time shaft 7 revolves. It will be understood of course that any desired number of wheels 16 may be mounted on shaft 7, and likewise a plurality of numbering machines may be carried on each such wheel.

Instead of such numbering machine, various other printing forms of desired dimensions may be employed for mounting in blocks 19, such as 25 rubber printing plate 32 (Fig. 8).

Side members 1 and 2 are further connected by tie rod 33 to ensure rigidity of the structure. Cams 34 and 35 are eccentrically keyed to the respective ends of cross shaft 36 journalled in side members 1 and 2 and are adapted to be rotated by action of arm 37 and link 38 when members 12 are slidably adjusted to move the lithograph cylinder away from the impression cylinder. Since such cams bear against press frame members 5 and 6, such movement of members 12 is likewise operative to swing the supplemental frame comprising side members 1 and 2 about 30 shaft 30, whereby said frame is pivotally mounted in brackets 3 and 4, to move the numbering machines 22 or other such printing forms out of position to contact cylinder 8. Such movement is but slight and need not be operative to entirely 35 disengage gears 9 and 10 so that readjustment will not be necessary when the device is again put in use.

A special inking mechanism is provided in the form of an adjustable fountain 39 mounted on brackets 40 carried by side members 1 and 2. The ink is transported from steel fountain roller 41 to steel distributor or vibrator roller 42 by means of the composition transfer or doctor roller 43 mounted for oscillatory movement about shaft 44 which also acts as a supplemental tie-rod connecting members 1 and 2. Inking rollers 45 and 46 are journalled in arms 47 and 48 respectively adjustably mounted on brackets 49 on frame members 1 and 2. Such rollers 45 and 46 may therefore be adjusted to engage distributor roller 42 and at the same time be positioned to ink the rubber form of the numbering machines or other similar device carried by shaft 7. The driving means for the inking mechanism is not shown and may be of conventional gear or chain and pinion type.

It will therefore be seen that I have provided a supplemental or auxiliary printing mechanism which may be employed in conjunction with the impression cylinder of a lithograph printing press

and which may readily be moved into inoperative position when desired. As a matter of fact, by disconnecting link member 31, frame members 1 and 2 and the entire mechanism may be swung back and up out of the way should further access to the impression cylinder be desired. It is obvious that such mechanism is easily adjustable to prepare the same for a wide variety of purposes and that numbering or other local printing of sheets after they have passed from the lithograph cylinder may be accomplished without in any way interfering with the ordinary operation of the press.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a printing press having main frame members and a metal surfaced impression cylinder rotatably mounted therebetween and cooperating with a rubber surfaced lithographic transfer cylinder, an auxiliary printing mechanism comprising a supplemental frame including interconnected side members, said supplemental frame being pivotally mounted on said main frame members, a shaft journalled between said side members, said shaft extending parallel to said impression cylinder, a wheel mounted on said shaft and adapted to contact said impression cylinder to hold said shaft and supplemental frame in predetermined spaced relation thereto, means for rotating said shaft and impression cylinder in timed relation, a printing form of relatively narrow dimensions compared to said impression cylinder adapted to be adjustably positioned along said shaft to engage said impression cylinder when said wheel is in contact with the latter, and means for swinging the supplemental frame out of operating position.

2. In a printing press having main frame members and an impression cylinder rotatably mounted therebetween and cooperating with a transfer cylinder, a swingable auxiliary printing mechanism comprising a supplemental frame including interconnected side members, said supplemental frame being pivotally mounted on said main frame members, cam means to swing said supplemental frame, a shaft journalled between said side members, said shaft extending parallel to said impression cylinder, a wheel mounted on said shaft and adapted to contact said impression cylinder to hold said shaft and supplemental frame in predetermined spaced relation thereto, means for rotating said shaft and impression cylinder in timed relation, a printing form of relatively narrow dimensions compared to said impression cylinder adapted to be adjustably positioned along said shaft, said form being adapted to engage said impression cylinder when said wheel is in contact with the latter, means for inking said form supported by said supplemental frame and throw-out means including slideable bearings mounting one of said cylinders and a connection to said cam means, to place said cylinder in inoperative position and also to swing said supplemental frame out.

JOSEPH F. JIROUSEK.
